UNITED STATES PATENT OFFICE.

JAMES K. DIAMOND, OF GRAND RAPIDS, MICHIGAN, ASSIGNOR TO CLIPPER BELT LACER COMPANY, OF GRAND RAPIDS, MICHIGAN.

MACHINE FOR APPLYING FASTENERS TO BELTS, BLOW-OUT BOOTS, AND THE LIKE.

Application filed September 28, 1925. Serial No. 59,071.

My improved fastener device is especially designed by me for applying such fasteners although it is well adapted for the applying of belt lacing fasteners to belts especially 5 where machines of large capacity are required.

The main objects of this invention are:

First, to provide an improved fastener applying machine which is simple and easy 10 of operation and of very large capacity.

Second, to provide a machine of the class described having a wide range of adaptability to articles of different thicknesses.

Third, to provide a machine of the class 15 described by means of which the fasteners are very effectively applied.

Fourth, to provide in a machine of the class described a means for stripping or removing the fastener supporting card therefrom after the fasteners have been placed 20 in the machine.

Objects relating to details and economies 25 of construction and operation of my invention will definitely appear from the detailed description to follow. The invention is clearly defined and pointed out in the claims.

A structure which is a preferred embodiment of my invention is clearly illustrated 30 in the accompanying drawing, forming a part of this application, in which:

Fig. 1 is a front perspective view of a machine embodying the features of my invention.

Fig. 2 is a rear perspective view thereof.

Fig. 3 is a detail vertical section on a line corresponding to line 3—3 of Figs. 5 and 8.

Fig. 4 is a front perspective view showing the stripper in actuated position.

Fig. 5 is a plan view, parts being omitted and other parts being broken away for convenience in illustration.

Fig. 6 is a fragmentary front perspective view with the stripper in its retracted position.

Fig. 7 is an inverted view of the bed of the machine showing details of the movable jaw operating means.

Fig. 8 is a detail section on a line corresponding to line 8—8 of Figs. 3 and 5.

Fig. 9 is an enlarged fragmentary section corresponding to that of Fig. 3 with fasteners arranged in the holder, the operative

relation of the stripper to the fastener holder card being indicated by dotted lines. 55

Fig. 10 is a detail section corresponding to Fig. 9 of the jaws in closed position.

Fig. 11 is a detail view showing details of the actuating means for the stripper.

In the drawings similar reference characters refer to like parts in all of the views, and the sectional views are taken looking in the direction of the little arrows at the ends of the section lines.

Referring to the drawings, the pedestal 1 is of suitable character to support the bed 60 of the machine which comprises a base section 2 and a top section 3, the bed being made sectional for convenience in manufacture.

The machine illustrated is power operated, the shaft 4 being provided with a pulley 5 and with an automatic throw-out clutch mechanism designated generally by the numeral 6, this clutch mechanism being controlled from the foot pedal 7. The details of the clutch are not illustrated but it will be sufficient to state that it is adapted to throw out on each complete actuation. 70

The foot pedal 7 has a second actuating 80 lever 8 associated therewith and provided with a pedal 9 projecting at the front of the machine, the pedal being shown swung up against the pedestal in Fig. 1. This second lever 8 is provided with a hook 10 engaging the pedal 7 so that the pedal 7 may be operated independently of the lever 8 or actuation of the lever 8 will actuate the pedal. 85

The bed member 3 is provided with a seat 11 for the relatively fixed or anvil jaw 12, 90 this jaw being adjustably mounted on the seat, and is a relatively fixed jaw in operation. The jaw 12 is adjustably secured to its seat by means of the bolts 13 engaging the longitudinal slots 14. An adjusting 95 wedge 16 engages the rear inclined edge 17 of the jaw, the wedge being provided with an adjusting screw 18 having a hand wheel 19. This adjustment provides for adaptation of the machine to different thicknesses 100 of material in which the fasteners are to be set.

Below the front end of the jaw 12 is an upwardly facing curved bearing 20 for the coacting jaw 21, this jaw 21 being segmental 105 in cross section and rotatably supported in

the bearing. The jaw 21 is provided with a segment 22 having curved segmental ways 23 at each side. These ways are engaged by rollers 24 which hold the jaw 21 to its bearing. The rack 25 reciprocates in ways 25' in the bed member 2 of the machine. This rack is actuated from the connecting rod 26 engaging the crank 27 on the shaft 4.

The shaft 4 is provided with a drum 28 with which the brake band 29 coacts, this brake band being adjusted by means of the screw 30, the brake serving to prevent overthrow of the shaft 4.

To prevent injury to the parts, the connecting rod 26 is provided with a yielding connection to the rack 25, this connection consisting of the tubular coupling member 31 having a resilient block 32 therein coacting with the thrust member 33 on the end 20 of the connecting rod. A gland-like retaining member 34 is provided for this thrust member 33. This member 34 may be adjusted to take up any lost motion between the parts in the normal operation but the block 32 will yield when the parts are subjected to undue stress.

The jaw 21 is provided with a fastener holder 35 having a series of transverse slots 36 therein adapted to receive the fasteners 37. This holder 35 is pivoted at 38 on a bar 39 mounted on the upper side of the jaw 21 thereby permitting limited pivotal movement of the holder 35. The jaw 21 is provided with a face member 40 of suitable wear resisting material.

The holder has a hole 41 therein extending transversely through the slots 36 to receive the fastener retaining pin 42. This fastener retaining pin is carried by a slide 43 reciprocating in the way 44 projecting at the side of the machine. This slide is provided with a handle 45. The hole 41 of the fastener holder is substantially the axial center of the rotating jaw so that the rotation of the jaw does not put undue stress upon the pin while the pin is in engagement.

With this arrangement a set of fasteners supported by a card 46 are placed in the holder and the slide 43 actuated to engage the pin thereby securing the fasteners in the holder.

I also provide means for disengaging the card or stripping the card from the fasteners, and this in the embodiment illustrated 55 consists of the stripper 47 having a plurality of fingers or teeth 48 adapted to enter slits 49 in the jaw 12 when the stripper is in retracted position, the stripper being projected to engage the card 46, the fingers or teeth passing between the fasteners.

The supporting and operating means for the stripper, in the structure illustrated, comprises a pin 50 engaging the forwardly inclined slot 51 in the stripper. The rear 65 end of the stripper is downwardly inclined

at 52. A lever 53 is pivoted at 54 on the jaw 12 which is slotted at 55 to receive the lower end of the lever. This lever is provided with a finger 56 engaging the inclined rear end of the stripper and a second finger 70 57 engages the under side of the stripper.

A spring 58 is connected at 59 to the lever and at 60 to the stripper, the connection 60 being well toward the forward end of the stripper.

By this supporting and operating means, when the lever 53 is moved forwardly, the stripper is actuated with a combined reciprocating and tilting movement, engaging the fastener card and stripping it from the 80 hooks of the fastener.

To further control the path of movement of the stripper, a forwardly curved guide bearing 62 is provided for the rear end of the stripper, see Fig. 11. The stripper is 85 returned to its retracted position by means of the coiled spring 63.

My improved machine is of very large capacity and is operated with little effort on the part of the operator.

The structure illustrated is, as stated, especially designed for the applying of fasteners to the edges of blowout boots and the like. It is, however, well adapted for use in applying fasteners of this type generally.

I have illustrated and described my invention in an embodiment which I have found very practical. I have not attempted to illustrate or describe certain modifications and adaptations as I believe the disclosure 100 will enable those skilled in the art to embody or adapt my improvements as may be desired.

Having thus described my invention, what I claim as new and desire to secure by Letters Patent, is:

1. In a structure of the class described, the combination of a jaw having a plurality of longitudinal slits in its face, a coacting movable jaw, a fastener holder adapted to support a plurality of fasteners operatively associated with said jaws, a stripper provided with teeth spaced to enter the slits in said jaw, said stripper having a forwardly inclined slot therein and a downwardly inclined rear end, a supporting pin engaging said slot, a forwardly curved guide for the rear end of said stripper, an actuating lever having a pair of spaced fingers, one of which engages the under side of said stripper and the other the said inclined rear end thereof, and a spring connected to the top of said stripper member in front of the said supporting pin and to the said lever whereby the stripper member is actuated with a combined reciprocating and swinging movement.

2. In a structure of the class described, the combination of a jaw having a plurality of longitudinal slits in its face, a coacting movable jaw, a fastener holder adapted to sup-

- port a plurality of fasteners operatively associated with said jaws, a stripper provided with teeth spaced to enter the slits in said jaw, said stripper having a slot therein, a supporting pin engaging said slot, an actuating lever having a pair of spaced fingers, one of which engages the under side of said stripper and the other the rear end thereof, and a spring connected to the top of said stripper member in front of the said supporting pin and to the said lever whereby the stripper member is actuated with a combined reciprocating and swinging movement.
15. 3. In a structure of the class described, the combination of a jaw having a plurality of longitudinal slits in its face, a coacting jaw, a fastener holder adapted to support a plurality of fasteners operatively associated with said jaws, a stripper provided with teeth spaced to enter the slots of said fixed jaw, said stripper being mounted for combined reciprocating and swinging movement, and means for actuating said stripper.
20. 4. In a structure of the class described, the combination of a jaw having a slotted face, a coacting rotatably mounted jaw, a fastener holding means operatively associated with said rotatable jaw to support the fasteners in an outwardly inclined relation to said fixed jaw when the movable jaw is in its initial position, a stripper having a plurality of fingers adapted to be retracted into said slits, and means for actuating said stripper.
25. 5. In a structure of the class described, the combination of a jaw having a slotted face, a coacting jaw, a fastener holding means operatively associated with said jaws, a stripper having a plurality of fingers adapted to be retracted into said slits, and means for actuating said stripper.
30. 6. In a structure of the class described, the combination of a jaw having a plurality of slits in the face thereof, a coacting jaw, a fastener holder adapted to support a plurality of fasteners operatively associated with said jaws, and a stripper provided with teeth so spaced as to be retractible into said slits and adapted when the stripper is actuated to pass between the fasteners supported by said holder.
35. 7. In a structure of the class described, the combination of coacting jaws, a fastener holder adapted to support a plurality of fasteners in spaced relation operatively associated with said jaws, a stripper provided with teeth spaced to pass between the fasteners supported by said holder, said stripper being mounted for combined reciprocating and outward swinging movement on its work stroke, and means for actuating said stripper.
40. 8. In a structure of the class described, the combination of coacting jaws, a fastener holder adapted to support a plurality of fasteners in spaced relation operatively associated with said jaws, a stripper provided with teeth spaced to pass between the fasteners supported by said holder, and means for actuating said stripper.
45. 9. In a structure of the class described, the combination of coacting jaws, a fastener holder adapted to support a plurality of fasteners in spaced relation operatively associated with said jaws, a slide movable transversely of said jaws and provided with a fastener retaining pin adapted to retain the fasteners within said holder and engageable therewith by the reciprocation of said slide, a stripper provided with teeth spaced to pass between the fasteners mounted in said holder, and means for actuating said stripper.
50. 10. In a structure of the class described, the combination with a bed, of an anvil jaw member mounted thereon, said bed having an upwardly facing bearing disposed transversely below said jaw, a coacting movable jaw member of segmental cross section rotatably mounted in said bearing, a transversely slotted fastener holder mounted on said movable jaw member for limited pivotal movement, said fastener holder member having a longitudinal hole adapted to receive a pin transversely through said slots, a slide, and a retaining pin carried by said slide and aligned with said hole in said fastener member, said pin being disposed axially of said rotatable jaw.
55. 11. In a structure of the class described, the combination of coacting jaws, one of which is rotatably mounted, a transversely slotted fastener holder mounted on said rotatable jaw member for limited pivotal movement, said fastener holder member having a longitudinal hole adapted to receive a pin transversely through said slots, a slide, and a retaining pin carried by said slide and aligned with said hole in said fastener member, said pin being disposed axially of said rotatable jaw.
60. 12. In a structure of the class described, the combination of coacting jaws, a transversely slotted fastener holder operatively associated with said jaws and having a hole therein adapted to receive a pin transversely through said slots, a slide, and a retaining pin carried by said slide and aligned with said hole in said fastener member.
65. 13. In a structure of the class described, the combination of a bed, a jaw mounted on said bed, said bed having an upwardly facing bearing disposed transversely below said jaw, a coacting jaw rotatably supported in said bearing, a segment on said rotating jaw provided with a curved way, a slidably mounted rack coacting with said segment, a roller mounted on said bed to coact with said way for holding said rotating jaw in its

- bearing, an actuating means having a yielding thrust connection to said rack, and a fastener holder adapted to support a plurality of fasteners carried by said rotatable jaw.
14. In a structure of the class described, the combination of a bed, a jaw mounted on said bed, said bed having an upwardly facing bearing disposed transversely below said jaw, a coacting jaw rotatably supported in said bearing, a segment on said rotating jaw, a slidably mounted rack coacting with said segment, an actuating means having a yielding thrust connection to said rack, and a fastener holder adapted to support a plurality of fasteners carried by said rotatable jaw.
15. In a structure of the class described, the combination of an anvil jaw, a coacting jaw rotatably mounted, a segment on said rotating jaw provided with a curved way, a slidably mounted rack coacting with said segment, a roller coacting with said way for holding said rotating jaw in its bearing, an actuating means having a yieldable connection to said rack, and a fastener holder adapted to support a plurality of fasteners operatively associated with said jaws.
16. In a structure of the class described, the combination of an anvil jaw, a coacting rotatably mounted jaw, a segment on said rotating jaw, a slidably mounted rack coacting with said segment, an actuating means having a yieldable connection to said rack, and a fastener holder adapted to support a plurality of fasteners operatively associated with said jaws.
17. In a structure of the class described, the combination of a bed, a jaw mounted on said bed, said bed having an upwardly facing bearing disposed transversely below said jaw, a coacting jaw rotatably supported in said bearing, means for actuating said rotating jaw, and a fastener holder adapted to support a plurality of fasteners pivotally mounted on said rotatable jaw for limited movement thereon.
18. In a structure of the class described, the combination of a bed, an anvil jaw mounted on said bed, said bed having an upwardly facing bearing disposed transversely below said jaw, a coacting jaw rotatably supported in said bearing, means for actuating said rotating jaw, and a fastener holder adapted to support a plurality of fasteners operatively associated with said jaws.
19. In a structure of the class described, the combination of an anvil jaw member, a rotatably mounted coacting jaw, and a fastener holding means mounted on said rotatable jaw so that the fasteners carried thereby are swung on an axis substantially coinciding with that of the rotatable jaw.
20. In a structure of the class described, the combination of an anvil jaw member, a curved bearing disposed transversely of said anvil jaw, a coacting jaw of segmental cross section mounted in said bearing, and a fastener holder mounted on said rotating jaw.
21. In a structure of the class described, the combination of an anvil jaw member, a coacting rotatable jaw of segmental cross section, and a fastener holding means carried by said rotating jaw.
22. In a structure of the class described, the combination of an anvil jaw member, a bearing disposed transversely below said anvil jaw, a coacting segmental jaw mounted in said bearing the axis of the rotating jaw being in approximately the plane of the face of the anvil jaw member, and a fastener holder operatively associated with said jaws.
23. In a structure of the class described, the combination of a relatively fixed jaw, a coacting segmental rotatable jaw mounted below said fixed jaw with its axis in approximately the plane of the face of the fixed jaw, and a fastener holding means operatively associated with said jaws.
24. In a structure of the class described, the combination of an adjustably mounted anvil jaw member, a coacting jaw rotatably mounted below said anvil jaw member, and a fastener holder mounted on said rotating jaw.
25. In a structure of the class described, the combination of an adjustably mounted anvil jaw member, a coacting jaw rotatably mounted below said anvil jaw member, and a fastener holder means operatively associated with said jaws.
26. In a structure of the class described, the combination of a pair of coacting jaws, a fastener holder adapted to receive a plurality of fasteners, and a stripper operatively associated with said jaws and fastener holder and coacting therewith, for the purpose specified.

In witness whereof I have hereunto set my hand.

JAMES K. DIAMOND.
